CUTTING MACHINE

Samuel Segal, Brooklyn, N. Y.

Application January 31, 1936, Serial No. 61,818

7 Claims. (Cl. 51—249)

My invention relates to a cloth cutting machine having a reciprocable blade and improved means for sharpening the reciprocable blade. In cloth cutting machines of the type utilizing a vertically reciprocable blade difficulty has been experienced so far as I am aware to properly sharpen the blade while in its holder or guard. Although attempts were made hitherto to sharpen the reciprocable knife while secured in its holder the cutting edge produced was of such character as to be inadequate for heavy duty and would not stand up for any appreciable periods of time during use. Accordingly the present invention has as a primary object to provide in a cloth cutting machine vertically displaceable intermittently actuated vibratory sharpening means for its elongated reciprocable blade adapted to alternately process or grind opposite beveled faces of the blade to form a sharp edge substantially coextensive with the length of the blade even though the latter is in assembled relation with its vertical guard.

The invention has as another object to utilize an oscillator having freely mounted and rotatable grinding wheels straddling the reciprocable blade, and means for actuating the oscillator for periodically and alternately moving the grinding wheels against beveled faces of the blade during relatively rapid reciprocation of the latter.

The invention comprehends as a further object the provision of means for sharpening the lowest vertical part of the edge of the blade, during reciprocation thereof and controlled means for sharpening the lower horizontal edge of the blade during such reciprocation.

The invention contemplates as a further object the provision of a cloth cutting machine characterized in that a conveniently controlled clutch is utilized to operatively interconnect a prime mover with transmission means for rotating a double threaded screw whereby a carriage is reciprocably actuated for alternately lowering and raising sharpening means straddling the reciprocable blade.

The invention has as further object the provision of a cloth cutting machine of the character alluded to, in which the double threaded screw is operatively associated with means for intermittently and periodically actuating a swiveled or pivoted oscillatable support freely and rotatably sustaining the grinding or sharpening wheels straddling the reciprocable blade.

The invention also consists in certain new and useful features of construction and combination of parts hereinafter set forth and claimed and as

to other objects, advantages, the mode of its operation and manner of its organization, these inter alia, may be better understood by referring to the detailed description when considered with the accompanying drawings in which:

5

Fig. 1 is a side view of the cloth cutting machine according to my invention and showing its supporting base thereof partly in section.

Fig. 2 is a front view of Fig. 1.

Fig. 3 is a fragmentary and side view of Fig. 2. 10

Fig. 4 is a fragmentary and enlarged view of Fig. 1, illustrating the oscillatable sharpening means in position to process the lower vertical end of the reciprocable blade.

Fig. 5 is a sectional view taken on the line 5—5 15 of Fig. 1.

Fig. 6 is a sectional view taken on the line 6—6 of Fig. 2, illustrating the vibrator or oscillator, in a position where the left grinding wheel is against the edge of the reciprocable blade.

20

Fig. 7 is a view similar to Fig. 6, showing the oscillator in a neutral position with the grinding wheels thereof straddling the blade and spaced therefrom.

25

Fig. 8 is a view similar to Fig. 6, however, showing the right grinding wheel of the oscillator against the blade.

Fig. 9 is a sectional view taken on the line 9—9 of Fig. 2.

Fig. 10 is a sectional view taken on the line 30 10—10 of Fig. 2.

Fig. 11 is a section taken along the line 11—11 of Fig. 2, showing a sectional view of the reciprocable carriage operatively interconnecting the double threaded screw and slideable sleeve for reciprocably displacing the oscillator supporting arm and

35

Fig. 12 is a view taken on the line 12—12 of Fig. 11, illustrating a fragmentary portion of the double threaded driven screw.

40

Fig. 13 is a side view of the cutting blade.

Fig. 13A is a view on the line 13A—13A of Fig. 13.

Fig. 14 is an enlarged sectional view of one of the grinding wheels shown mounted on its arm 45 of the oscillator.

Fig. 15 illustrates the pivoted or swiveled connection for the oscillator taken on the line 15—15 of Fig. 3 and

Fig. 16 is a plan view of the presser foot taken 50 on the line 16—16 of Fig. 1.

The cloth cutting machine, according to the invention, comprises a base 10, a vertical channeled blade guard or holder 11 integral with a laterally and rearwardly extending arm 12 to 55

which is appropriately secured leg 13 depending from casing of the prime mover or motor 14. Also secured to arm 12 is a block 15 on which the lower part of the annual rim 16 of the casing is fixedly retained.

Extending laterally from block 15 is a suitable handle 18 for bodily moving the machine relative to a supporting surface 19. Associated with the top part of the motor casing is a pair of up-standing posts 20 electrically connected to the windings of the prime mover or motor 14. These posts are adapted to removably receive a plug or socket 21 appropriately connected to a source of electrical potential. To facilitate lifting the machine and carrying the latter from place to place, annular hand 16 of the casing of the prime mover is provided with a T shaped handle 22.

Fixedly attached to the shaft 23 of the prime mover is a relatively heavy counter balancing crank arm 24 having at one end thereof a forwardly extending pin 25 on which eye 26 of connecting rod 27 is swiveled while the lower end of the latter is operatively connected to the reciprocable cross head, generally denoted 28, having its rear portion slidably and vertically guided in groove 29 of the shoe or track 30 attached to plate 31 which in turn is appropriately secured to the depending leg 13 of the motor casing.

The cross head 28 includes a depending gear 32 carrying blade clamping means comprising a head 33, a shank 34, a washer or collar 35 and an adjustable nut 36. The spaced tines 37 of the upper bifurcated part of the cloth cutting blade 38 straddle shank 34 and the spaced tines 37 are brought against ear 32 of the cross head by head 33 upon the adjustment of the clamping nut 36.

The elongated blade is provided with a plurality of perforations 39, arranged in staggered fashion, vertically disposed beveled faces 39 to define the vertical cutting edge 40, and lower beveled faces 41 to form the inclined cutting edge 42.

The blade is slidably guided in an elongated vertical striation or gap 43 formed by a pair of closely spaced metal leaves or bearings 44 in the form of elongated strips fixedly retained in the rigid channeled guard or holder 11.

With the socket 21 attached to posts 20, power to the motor or prime mover may be supplied by operating the swingable handle or switch 45 which is directly connected in the motor circuit and may either make or break the latter as is well understood.

Where the electrical circuit to the motor is completed the cross head 28 will be vertically reciprocated and consequently the blade will be similarly reciprocated relative to the guide 11.

Associated with the rear shoe 30 is a companion front channeled shoe 46 and fixedly secured to the latter is a bracket or frame generally designated 47. Shoes 30 and 46 form complementary vertical members for reciprocably guiding cross head 28. Specifically, however, bracket or support 47 comprises a vertically disposed rear wall 48 fixedly although removably secured to the shoe 46 by screws 49. The one piece bracket 47 also includes a transverse side wall 50 integral with rear vertical wall 48 and the spaced upper and lower forwardly projecting shelves 51 and 52. The unitary bracket is utilized to support the mechanism driven by the prime mover for the dual purpose of vertically reciprocably sharpening supporting means and of oscillating the

sharpening means straddling the exposed cutting edge of the blade 38.

More particularly rear wall 48 of the bracket 47 and a bearing 53 secured to an expanded portion of transverse wall 50 thereof, guide rotational movement of a stub shaft generally indicated 54, that is, its larger end 55 is journalled in rear wall 48 while forward end 56 is reduced and journalled in bearing 53 mounted on an expanded portion 56' overhanging transverse wall 50.

Stub shaft 54 is provided with a worm 57 adapted to mesh or interlock with a complementary worm gear 58 to which is connected the companion beveled gear 59. In other words, if the worm gear 58 is rotated, beveled gear 59 will be bodily rotated in synchronism therewith. If desired the beveled gear 59 and worm gear 58 may be of one piece or each may be made separately and suitably fused together. For purposes of specifications, however, the worm gear 58 and beveled gear 59 are both rotatably retained on a horizontal stub shaft 60 and therefore both rotate in unison in respect thereto, the stub shaft 60 being appropriately secured to the upper part of the transverse wall 50 of the bracket or frame 47.

According to my invention, worm shaft 54 may be slidably moved towards or away from the prime mover. In this connection, it will be observed that the reduced portion 56 of the slideable and rotatable shaft 54 is provided with an annular flange 61 forming with the forward end of the worm 57 spaced abutment walls when selectively actuated by a rotatable disc 62 interposed therebetween. This disc 62 (Figs. 9 and 10) is rotatably carried on a pin 63 secured to an upper offset portion 64 of the elongated lever 65 having its intermediate portion pivoted on the expanded shank 66 (Fig. 2) of set screw 67 having its reduced inner portion 68 fixed to the transverse wall 50 of the bracket.

In the normal operation of the machine when utilized for cutting cloth or the like, the slideable and rotatable shaft 54 of course, is operatively disconnected from the prime mover. In such relation, clutch or arm 69 fixedly carried by the enlarged portion 55 of this stub shaft 54 is out of the path of travel or orbit of the driving pin 25 on which the upper part of the connecting rod 27 is swiveled. In other words, rotatable clutch 69 is free of pin 25 of the prime mover when the machine is to be used for cutting cloth.

Specifically, however, control lever 65 is manually shifted to bodily move shaft 54 in respect to the prime mover. For this purpose, the manipulating handle 72 is utilized. This handle has its upper portion pivotally secured to transverse wall 50 of the bracket and also carries an eccentrically mounted disc or cam 74 which cooperates with lever 65 to pivot or tilt the latter about shank 66 of set screw 67 fixed to wall 50.

When control handle 72 is elevated or turned, cam 74 causes the upper offset portion 64 of lever 65 to move forwardly or away from the prime mover, that is, roller 62 abuts flange 61 and consequently shaft 54 and its worm 57 bodily and slidably move away from driving pin 25 associated with the prime mover. Therefore clutch 69 is moved out of the path of pin 25 (Fig. 10). It follows that although the blade may be reciprocated, the sharpening means for the blade is disconnected from the prime mover. It will be noted, however, that as the upper part of lever 75

65 is moved away from the prime mover, the lower part 75 thereof moves towards the prime mover and against the helicoidal spring 76 having its rear end retained in the recess 77 and its forward end abutting the lower part 75 of lever 65 although encircling pin or post 78 carried by lower part 75.

If the manipulating handle 72 is rotated to point downwardly as indicated in Figs. 2 and 3, cam 74 moves away from or becomes free of lever 65 and consequently spring 76 expands thus automatically moving lower part 75 of lever 65 forwardly while its upper offset portion moves rearwardly. It follows that roller 62 is moved automatically towards the prime mover causing stub shaft 54 to be bodily and slidably shifted towards pin 25. Hence clutch 69 is arranged in the orbit or path of the driving pin 25, thus establishing a driving connection between the prime mover and the transmission comprising beveled gears 80 and 59, worm gear 58 and worm 57.

The horizontal beveled gear 80 is appropriately pinned or fixed to the vertically disposed elongated and hollow screw generally denoted 81 rotatably disposed in the upper and lower shelves 51 and 52 of the bracket in suitable bearings 82 and 83 respectively.

Interconnecting screw 81 and a vertically guided slidable sleeve 84 is a reciprocable carriage, broadly designated 85, which includes a block 86 closely confined in an opening 87 thereof. Block 86 is provided with a single tooth 88 constantly and slidably guided by and within an endless double threaded groove, generally designated 89 which consists of helicoidal groove 90 for guiding tooth 88 downwardly and the helicoidal and communicating groove 91 for guiding tooth 88 upwardly, the companion upper ends and lower ends of the helicoidal grooves 90 and 91 being interconnected by a curved groove as 92 shown schematically in Fig. 12 and in dotted lines in Fig. 2. Hence a continuous but double threaded groove is formed in the driven screw 81 and by reason of tooth 88 being guided thereby, carriage 85 is driven in a rectilinear direction to complete a full down stroke and thereafter driven linearly but upwardly to complete a full return stroke, that is, the carriage is reciprocated during rotation of the screw provided the clutch is operatively connected to the prime mover as hereinbefore described, it being noted, however, that flattened tooth 88 of the carriage is firmly retained within the double threaded screw 89 by a plate 93 held against the forward wall of the carriage by suitable fastening means 94.

Carriage 85 is held fixed with respect to the vertically slidable sleeve 84 by the clamping bolt 95, and since the carriage is reciprocated by reason of the action of screw 81, it follows that sleeve 84 carried by the carriage, in turn, will be reciprocated although guided in this movement by the elongated fixed spindle 96 retained against rotation by set screw 97 in the upper shelf 51 of the bracket.

Cylindrical spindle 96 guides reciprocable displacement of sleeve 84 and consequently the latter is alternately projected and retracted on each down and up stroke respectively of the carriage.

Fixedly attached to the lower part of slidable sleeve 84 is an L shaped arm 98 which has a horizontal and intermediate portion provided with a bearing or bushing 99 rotatably guiding the cylindrical elongated rod 100 having a verti-

cal key way 101 (Fig. 9) receiving key or lug 102 fastened to hollow double threaded screw 81. It follows therefore if screw 81 be rotated, the coupled or keyed rod 100 will be correspondingly rotated in synchronism. It will be noted, however, that L shaped arm 98 is provided with an upstanding hollow boss 103 which is rigidly secured to the lower portion 94 of the reciprocable sleeve 84 by the clamping bolt 105 while lower shelf 52 of the bracket includes an appropriate guide bearing 106 closely surrounding sleeve 94 but permitting longitudinal displacement thereof.

With clutch 69 connected to the driving pin 25 the double threaded screw 81 will be rotated if shaft 23 of the prime mover is rotating. It follows therefore that shaft 100 which is coupled to screw 81 will likewise be rotated and therefore cog or spider, broadly denoted, 106 rigidly attached to the lower end of the driven shaft 100 is correspondingly rotated.

Spider 106 comprises three outwardly extending and similar teeth or vanes 107, 108 and 109, arranged one hundred and twenty degrees apart for periodically cooperating with inwardly and oppositely arranged projections or cams 110, 111 integral with the swiveled oscillator comprising loop or ring 112 and an integrally connected fork or bifurcation 113 comprising a pair of diverging arms 114 and 115 facing towards and straddling the reciprocable blade 38 retained in holder 11.

Arms 114 and 115 each rotatably and slidably support a cylindrical shaft 116 each appropriately holding at its inner end a sharpening or grinding Carborundum wheel 71. More particularly each grinding wheel 71 is provided with fixed bearing or bushing 118 (Fig. 14) comprising a hollow cylindrical shank 119, a flange 120 and the flared flange 121 formed by upsetting shank 119. The flanges 120 and 121 (Figs. 6 and 14) together with their shank 119 have a friction and tight fit with the central reduced and perforated portion of the bore of the grinding wheel while its axle or shaft 116 is provided with an annular shoulder 116' to prevent displacement of the bushing in one direction and the shaft 116 includes an upset wedge 122 to prevent displacement of the bushing in an opposite direction, the bushing having a relatively tight fit with its shaft 116 and bodily rotates therewith but shaft 116 is slidable relative to its supporting arm of the vibrator or oscillator and is provided with head or stop 123 to prevent removal thereof.

More particularly oscillator or fork 113 is provided with a fixed upstanding pin 124 which is rotatably supported in the bore 125 extending through arm 98 and its upstanding boss 126. However, rotatable pin 124 (see Fig. 15) is provided with an annular groove 127 in which the inner end of shank 128 of set screw 129 is arranged. In other words, shank 128 constitutes means for rotatably supporting pin 124 which is guided in bore 125 and consequently oscillator or vibrator 113 can swivel or pivot in respect to its support 98.

In Fig. 7, the grinding wheels 71 are in neutral position although cog 106 is rotating as indicated by the arrow. Further rotation of the cog in the same direction causes tooth 107 to strike cam 110 and consequently oscillator 113 is bodily rotated or swung in a direction corresponding to the direction of rotation of the cog and therefore arm 115 of the oscillator moves towards the blade while arm 114 moves away from the blade. Therefore grinding wheel 71 which is carried by

arm 115 and which is rotatably mounted on to shaft 116 moves against an adjacent beveled edge of the blade 38 (Fig. 8) to process the latter until tooth 107 of the cog leaves cam 110. 5 Shortly thereafter tooth 108 of the cog strikes cam or tooth 111 of the oscillating fork 113, hence causing the latter to bodily and horizontally swing or rotate in a direction counter to the rotation of the cog as indicated by the arrow 10 in Fig. 6. Thus grinding wheel 71 rotatably carried by arm 114 of the oscillator moves in contact with the opposite beveled face of the blade while the grinding wheel of arm 115 moves away from the blade and such contact with the 15 blade will be maintained until tooth 108 leaves cam 111.

On each revolution of cog 106 each tooth thereof causes the oscillator 113 to swing in one direction and subsequently in an opposite direction. 20 Hence where the cog is provided with three teeth as illustrated, the oscillator will complete three complete vibratory cycles for each revolution of the cog. A complete vibratory cycle for purposes of definition may be said to comprise a 25 throw of the oscillator in one direction to process one side of the blade plus a throw of the oscillator in an opposite direction to process the opposite side of the blade. Of course while a grinding wheel 71 comes in contact with the reciprocating 30 blade, such wheel will be set in rotation to facilitate sharpening of the blade.

By the present invention, it is apparent that the cog constitutes means for periodically actuating the oscillator 113, thereby permitting alternate and intermittent processing of opposite faces of the blade. If it is desired to increase the rate of vibration of the oscillator it is within the province of the invention to provide a cog having more than three teeth. However, in practice 40 and from experience it has been discovered that alternate impacts on the opposing faces of the knife edge due to the operation of a three toothed cog of the type shown produces the required cutting edge and further that such edge will 45 stand up for relatively long periods even though subjected to relatively heavy work consisting of a multiplicity of layers of cloth or the like 130 (Fig. 1).

The present theory of sharpening a reciprocable 50 blade by vibratory means in a cloth cutting machine so far as I am aware constitutes a distinct departure over the means for sharpening blades hitherto employed in that the former devices of the prior art for the same purposes herein disclosed were concerned with grinding means continuously in contact with the edge of the blade during reciprocation thereof. Although a certain edge with these older devices was formed, such edge, it has been discovered, has a relatively short 55 duration under actual working conditions and could not stand up under appreciable periods of time and instead of cutting the work as desired, the cloth will tear.

According to the principle of sharpening blades 60 herein disclosed, the blade although reciprocating is intermittently processed and alternately on opposite faces of the blade but in a relatively fast fashion whereby a cutting edge is provided of desired strength and having the necessary cutting qualities to penetrate a large bulk of cloth or other material comprising many superimposed layers.

Further in accordance with the present invention provision has been made for keeping the 75 blade relatively cool and lubricated although re-

ciprocating rapidly during periods of cutting or sharpening. In this connection, it will be observed, that apart from the staggeredly arranged and spaced perforations 39 in the body of the blade, the latter also includes inclined lubricant 5 retaining grooves 131 disposed on the opposite faces of the body of the blade and each interconnecting with a pair of adjacent openings 39. These relatively narrow and shallow grooves guide any lubricant dripping from the openings and 10 serve to retain such lubricant where the latter is of the liquid type and if desired a graphite lubricant of the solid type may be employed in connection with openings 39. Lubricant spilling from openings 39 and grooves 131 lubricate the body 15 of the blade as it reciprocably slides in its holder or guide 11 between the spaced leaves 44.

Slidably disposed and guided between the transverse wall 50 of the bracket 47 and a vertical track 133 which is secured to wall 50 is an 20 adjustable square shaped rod 134 having its lower end rigidly secured in boss 135 carried by the cloth pressure foot 136 (Figs. 1 and 16) comprising spaced arms 137 and 138 defining a tapered slot 139 adapted to permit the passage of 25 the reciprocable blade 38 into and through stria- 30 tion or slot 140 (Fig. 1) of a disc 141 from which guard or holder 11 upwardly extends. The presser foot 136 is provided with a reflexed handle or ear 142 adapted to be grasped by the operator to slid- 35 ably adjust the presser foot in respect to the lay- 40 ers of cloth 130.

However, the cloth presser foot may be manually adjusted when the horizontal brake arm 143 (Figs. 3 and 5) is released from vertical rod 134. 35 The brake arm 143 has a flattened rear end pivotally connected to a shank of a set screw 144 carried by a crank arm 145 connected to rotatable rod 146 (Figs. 3 and 5) journalled in leg 13 of the motor casing and the block 31 associated 40 therewith.

Control means for manipulating rockable rod 146 is in the form of a lever 147 (Fig. 1) having one end pivoted in a slot 148 and on set screw 149 carried by rod 146. Lever 147 is normally re- 45 tained in an elevated position by the free offset end 149 of a spring 150 having its intermediate portion 151 coiled about rod 146, and its other end or arm 152 is retained in a groove 153 of a set screw 154 fastened to block 31. 50

When control lever 147 is depressed free portion 149 of spring 150 is also depressed and consequently arm 152 thereof is flexed. However, if lever 147 is depressed, rod 146 is rotated or rocked, thereby causing crank arm 145 to be correspondingly displaced. Thus brake arm 143 is moved rearwardly and becomes free of the vertical and 55 slideable rod 134 of the presser foot which falls automatically to compress the several layers of 60 cloth mounted on base 10.

Upon removal of manual pressure from control lever 147, arm 155 of the spring 150 loses its energy and automatically elevates lever 147. Hence the brake arm 143 is rotated in a counter- 65 direction and moves against the slideable and adjustable rod 134, holding the latter in a locked or set position.

Appropriately journalled within the base 10 of the machine and below disc 141 which supports 70 guard or holder 11, is a pair of blade sharpening rollers 150 and 151. Specifically, however, each of these rollers is rotatably carried in bearing blocks 152 and 153 (Figs. 1 and 2) slidably guided in channels 154 and 155 in base 10 and these 75

bearings are retained in their channels by an appropriate removable cover plate 156.

Cooperating with each slideable bearing 152 and 153 is a helicoidal spring 157 which normally urges its bearing towards the center of knife receiving striation or slot 140. The object of rollers 150 and 151 is to sharpen the lower horizontal and slightly inclined edge 42 of the blade. Such edge is desired to overcome clogging of knife receiving slot 140 and to keep the latter clean during movements of the blade in guide 11.

To render sharpening rollers 150 and 151 ineffective, the latter may be separated against the resistance of springs 157 by rotating spindle or shaft 161 (Figs. 1 and 2) for displacing cam 162 carried by the latter. Where the manipulating wheel 163 is grasped and rotated, shaft 161 is rotated, and consequently cam 162 is displaced, causing lugs 164 and 165 depending from the 20 slideable bearings 152 and 153 to spread apart. Subsequently, however, the ends 166 of the cam coat with lugs 164 and 165 holding these a predetermined distance apart and preventing displacement of the slideable bearings towards each 25 other until rod 161 is again manipulated to release the widest portion of the cam from the depending lugs. In their linear displacement lugs 164 and 165 are guided by slots 167 in the removable cover plate 156.

Briefly recapitulating the operation of the herein machine, to cut a stack 130 of layers of cloth, the latter is placed on a suitable table and the handle 18 is grasped to move lip 168 of the base of the machine under the stack 130, after which, control handle 147 is depressed. The presser foot 136 falls by gravity and onto the upper lever of the stack, thus holding the latter against the base of the machine. Downward displacement of the presser foot is limited, however, by stop pin 171 which may strike the upper end of track 133 (Fig. 2). Of course where the machine is used for cutting purposes, the oscillatable means 113 supporting the rotatable grinding wheels 71 should be first arranged as to be near the top of the blade (Figs. 1 and 2). This may be accomplished manually or automatically. In the first case, hand wheel 70 associated with shaft 23 (Fig. 1) would be manually turned until the carriage 85 is at the top of the screw 81. In the second case, switch 45 may be thrown to cut the prime mover in circuit and with the clutch "thrown in" with the prime mover, the latter is operated until the carriage is at the top of the screw after which the clutch is disconnected from the motor.

With the clutch 69 mechanically disconnected from the prime mover, the sharpening means 71 ineffective at the top of the blade, and the presser foot holding the stack of cloth down, the switch 41 is thrown to close the electrical circuit for the prime mover and the blade is caused to reciprocate. The operator then grasps handle 18 and bodily moves the machine on the supporting rollers 170 and into the work which is in part supported by lip 168 of base 10 and subsequently guides the reciprocating blade along a guide line on the top layer of the work as is well understood.

When it is desired to sharpen the blade, the machine is removed from the stack of cloth, control lever 147 is depressed to release brake arm 143, thus permitting the presser foot 136 to fall to its lower position which is controlled by the stop pin 171 (Fig. 3) striking the track or guide 133. In such case presser foot 136 would rest on base 10. Handle 72 is then thrown downwardly, causing eccentric or cam 74 to shift lever 65 for

moving the clutch into engagement with driving pin 25. In such relation the clutch is continuously in the path of pin 25 of the relatively heavy crank 27 associated with the prime mover. Hence motion imparted by the prime mover is transmitted to the companion bevel gears 59 and 80. Therefore the double threaded screw 81 is set in rotation and carriage 85 moves first downwardly and subsequently upwardly traversing the entire length of the screw on each cycle of the 10 carriage.

If the carriage is reciprocated, sleeve 84 is also reciprocated and consequently the oscillator supporting arm 98 is reciprocated. However, during this operation, shaft 100 is rotated and cog 106, 15 causing the oscillator 113 to rock or swivel as previously pointed out. Hence the reciprocating blade is interruptedly or intermittently processed by the grinding wheels. First one part of one face of the blade is processed. Subsequently another part of the opposite face of the blade is processed although the blade is reciprocating. Such cycle of sharpening is continued for a relatively brief period of time to form the required knife edge and thereafter the clutch is disconnected from the prime mover. It should be noted, however, that during the interrupted sharpening operation, the lower vertical part of the blade is also sharpened by wheels 71 (Fig. 4) and if the sharpening rollers 150 and 151 have been 30 previously set by actuating thumb piece 163 to be closely disposed, then the lower horizontal edge 42 of the blade is processed since at the end of each downward stroke thereof during reciprocation it passes through slot 140 and contacts 35 the sharpening rollers 150 and 151 and if desired oscillator 113 may be provided with a depending boss 180 adapted to automatically abut and shift foot 136 against the resistancy of brake arm 143 on the first complete downward stroke of the 40 blade and dispose said presser foot against base 10 to be out of the path of the oscillator on successive down strokes thereof.

As many changes could be made in the above construction and many apparently widely different embodiments of the invention could be devised without departing from the scope thereof, it is intended that all matter contained in the above description or shown in the accompanying drawings shall be interpreted as illustrative and 50 not in a limiting sense.

I claim:

1. In combination, a prime mover, a blade, means connected to said prime mover for reciprocating said blade, a transmission, means for disconnectably connecting said transmission to said prime mover, a carriage, driven means actuated by said transmission for reciprocating said carriage, supporting means reciprocated by said carriage, an oscillator swingably sustained relative to said supporting means, a pair of grinding wheels straddling said blade and rotatably sustained by said oscillator and means associated with said driven means and cooperating with said oscillator to alternately shift said grinding wheels 60 into and out of contact with opposing faces of said blade during reciprocation of said oscillator and said blade.

2. In combination, a prime mover, a blade, means connected to said prime mover for reciprocating said blade, a transmission, clutch means for disconnectably engaging said transmission with said prime mover, a double threaded screw connected to said transmission, a carriage operatively connected to said screw and reciprocated by 75

the latter upon rotation thereof, a displaceable member reciprocated by said carriage, a support carried by said member, means swingable relative to said support comprising an oscillator, 5 means associated with said screw for vibrating said oscillator, and grinding wheels rotatably mounted on said oscillator and straddling said blade and adapted to impact opposing faces of said blade during reciprocation of said carriage and blade upon each cycle of vibration of said oscillator.

3. In combination, a prime mover, a blade, means connected to said prime mover for reciprocating said blade, a transmission, clutch 15 means for disconnectably engaging said transmission with said prime mover, a double threaded screw connected to said transmission, a carriage operatively connected to said screw and reciprocated by the latter upon rotation thereof, a 20 slidable member reciprocated by said carriage, a support carried by said member, an oscillator, swingably associated with said support comprising spaced arms and spaced cam means; a grinding wheel rotatably sustained by 25 each of said arms; and means comprising a spider bodily rotatable with said screw for severally and successively actuating said cam means for alternately moving said arms towards and away from said blade during reciprocation 30 of said blade and carriage.

4. In combination, a prime mover, a blade, means connected to said prime mover for reciprocating said blade, a transmission, clutch means for disconnectably engaging said transmission with said prime mover, a double threaded screw connected to said transmission, a carriage operatively connected to said screw and reciprocated by the latter upon rotation thereof, a 35 slidable member reciprocated by said carriage, a support carried by said member; an oscillator, swingably associated with said support, comprising a pair of spaced arms and a plurality of cams; a grinding wheel rotatably and slidably displaceable relative to each of said arms, and a 40 spider rotated by said screw and having a plurality of teeth each adapted to severally and successively contact said cams of said plurality for swinging said oscillator to permit the grinding wheel of one of said arms to contact one face of said blade during reciprocation thereof and simultaneously move the grinding wheel of the 45 remaining arm of said pair away from an opposite face of said blade.

5. In combination, a prime mover, a blade, 55 means connected to said prime mover for reciprocating said blade, a transmission, clutch means for disconnectably engaging said transmission with said prime mover, a screw connected to said transmission, a carriage operatively connected to said screw and reciprocated by the latter upon rotation thereof, a slidable

member reciprocated by said carriage, a support carried by said member, an oscillator, swingably associated with said support, comprising a pair of spaced arms and a plurality of cams, a grinding wheel rotatably supported by each of 5 said arms, a spider rotated by said screw and having a plurality of teeth each adapted to severally and successively actuate said cams of said plurality on each cycle of vibration of said oscillator and wherein each cycle consists of first 10 swinging said oscillator in one direction to permit one of said grinding wheels to contact one face of said blade during reciprocation thereof and simultaneously moving the remaining grinding wheel away from the opposite face of said 15 blade, and subsequently swinging said oscillator in an opposite direction to permit the grinding wheel previously out of contact with said blade to contact said opposite face of said blade during reciprocation of said blade and simultaneously moving the grinding wheel previously in contact with said reciprocating blade away from and out of contact with said first mentioned face of said blade.

6. In a cutting machine of the class described, 25 a prime mover, a base, a guard interposed between said base and prime mover, a blade slidably guided within said guard, means associated with the prime mover for reciprocating said blade, slidable presser means, a support operatively connected to said prime mover and reciprocated by the latter, oscillatable sharpening carrying means carried by said support, controlled brake means for resisting displacement of said presser means, and means associated with 30 said oscillatable sharpening carrying means for moving said presser means downwardly towards said base against the resistance of said brake means on the initial downward stroke of said reciprocable support.

7. In a cutting machine of the class described, 40 a prime mover, a base, a guard interposed between said base and prime mover, a blade slidably guided within said guard, means associated with said prime mover for reciprocating said blade, slidable presser means, a support operatively connected to said prime mover and reciprocated by the latter, an oscillator carried by 45 said support, rotatable sharpening wheels carried by said oscillator and adapted to straddle the fore part of said blade during reciprocation of the latter, controlled brake means for resisting displacement of said presser means, and means carried by said presser means adapted to be contacted by said oscillator for moving said 50 presser means downwardly towards said base against the resistance of said brake means on the initial downward stroke of said reciprocable support.

SAMUEL SEGAL. 60
